UNITED STATES PATENT OFFICE.

EDGAR W. CLEVELAND, OF HOLLAND, MICHIGAN.

JOURNAL ADJUSTMENT FOR ARMS OF MULTIPLE-SPINDLE DRILLS.

1,413,004.

Specification of Letters Patent. Patented Apr. 18, 1922.

Application filed September 15, 1919. Serial No. 323,782.

To all whom it may concern:

Be it known that I, EDGAR W. CLEVELAND, a citizen of the United States of America, residing at Holland, in the county of Ottawa 5 and State of Michigan, have invented certain new and useful Improvements in Journal Adjustments for Arms of Multiple-Spindle Drills; and I do hereby declare the following to be a full, clear, and exact description of the invention, such as will enable others skilled in the art to which it appertains to make and use the same.

This invention relates to a journal adjustment for the arms of a multiple spindle 15 drill and is concerned in the provision of a very simple and particularly effective form of adjustable connection between the ends of the arms of said multiple spindle drill and the journal boxes carried at the ends 20 of said arms in which the drill spindles are mounted. In multiple spindle drills a number of arms are used to carry the drills, the arms being adjustably mounted on a common head or other support. The drills carried by the drill spindles are usually of different length and it is necessary, many times, 25 to drill holes in the work to different depths. From this it follows that the journal boxes carrying the drill holding spindles must 30 each be vertically adjustable on its respective arm. It is also necessary that such journal boxes shall be quickly and easily adjusted and that the means by which this adjustment is accomplished shall be readily accessible 35 so as to be easily operated whenever necessary. In the present invention a construction has been devised in which the attainment of all of these desired ends is accomplished while the construction itself is 40 relatively simple and economical to manufacture. Various other objects and purposes than those specifically stated will appear fully and in detail as understanding of the invention is had from the following description taken in connection with the accompanying drawing, in which:

Fig. 1 is a vertical section through the arm and attached journal box, the means for accomplishing the adjustment of the journal box on the arm being shown in side elevation.

Fig. 2 is a plan of the construction shown in Fig. 1.

Fig. 3 is a fragmentary horizontal section 55 taken substantially on the line 3—3 of Fig. 1.

Fig. 4 is a partial section and end elevation taken on the broken line 4—4 of Fig. 1.

Fig. 5 is a view similar to Fig. 1 illustrating a modification in construction. 60

Fig. 6 is a like view illustrating a still further modification in construction; and,

Fig. 7 is a plan of the construction shown in Fig. 6.

Like reference characters refer to like 65 parts in the different views of the drawing.

At one end of the arm 1 a member 2 is mounted, it being provided with a journal box 3 in which a drill spindle 4 is rotatably mounted, the same carrying a drill receiving 70 socket 5 at its lower end. The drill spindle is adapted to be held in vertical position. The member 2 lies against the end of the arm and is adapted to be adjusted to different positions vertically with respect to 75 said arm. The adjacent contacting parts of the arm and of the member 2 are formed with slots 6 and 7 adapted to come into conjunction with each other and in which a bar 8 may be located, the same being of a thickness to practically fill the slots and hold the member 2 against any lateral movement with respect to the arm. At its lower end bar 8 is turned to the rear and formed with a cylindrical projection 9 which is threaded 80 for a distance from its end. This part 9 extends through an elongated slot 10 which joins with the slot 8 at its upper part and which is made through the downwardly extended portion 11 of the arm, as shown. 90

The slot 6 at its upper part and within the arm 1 is widened as indicated at 12, whereby a T-slot is made. Likewise the slot 7 is widened at each side at the forward portion thereof and at the lower portion 95 of the member 2 as indicated at 13 making another T-slot. The bar 8 at its upper end is turned to the rear and has projecting portions 14 extending laterally at the end thereof of which portions are received in the widened part 12 of the T-slot in the arm 1. A projection 15 is made on each side of the bar 8 substantially at its middle point so that the same extends into the widened portion 13 of the T-slot in the member 2. A nut 100 16 is threaded onto the projection 9 and is adapted to tighten against the washer 17 bearing against the part 11 of the arm 1.

With this construction, when the nut 16 is tightened, it is apparent that the member 2 105 carrying the drill spindle is brought against the end of the arm 1 and is held securely

against any vertical movement, while a loosening of said nut 16 releases the same, permitting the projections 14 to traverse the part 12 of the T-slot in the arm in lowering the drill or the projections 15 to traverse the part 13 in the T-slot in the member 2, when the drill is elevated. A wide range of adjustment of the drill spindle, vertically, is possible with this construction as is evident. One nut only is required while the manufacture and assembly of the parts is very simple.

In Fig. 5 a slight modification in construction is shown, the bar 8^a taking the place of the bar 8 and being pivotally mounted at its upper end at 18 to the arm 1. The widened portion 12 making a T-slot in the first construction is not present in the construction shown in Fig. 5, but the slot 6^a is cut a little deeper at its upper end to permit the pivotal attachment of the upper end of the bar 8^a. Likewise the T-slot in the part 2 extends the full height thereof as indicated at 13^a. This gives a greater range of adjustment of the journal box than would be possible if the T-slot was only of the length shown in Fig. 1. The operation in adjustment of the journal box and the drill carried thereby, is substantially identical with that of the construction shown in Fig. 1.

In Figs. 6 and 7 a still further modification of construction is shown, the bar 8^b being pivotally mounted on a fixed pivot 19 between its ends on the member 2. The T-slot in the member 2 is not used and the slot 7^a is of greater depth than the slot 7 in the construction shown in Fig. 1, permitting the vertical portion of the bar 8^b to be entirely received within the part 2. The upper end of the lever 8^b is formed with lateral projections 14 received in the wider portions 12 of a T-slot in the end of the arm and action is in all respects similar to that of the construction shown in Fig. 1, except that the bar 8^b is fixed, except for a limited pivotal movement, on the journal box carrying member 2.

These constructions are very effective and very simple in operation and completely housed within the arm and journal box and out of sight. In Fig. 7 I have shown the rear side of the journal carrying member 2 as guided between projecting lips on the end of the arm 1. This is not really necessary as the bar 8 serves as a guide for the journal member 2 holding it against any lateral tilting action. There is nothing in the construction to get out of order and the adjustment can be quickly and easily affected by merely loosening the nut 16, moving the journal box to the desired place and then tightening the nut. This nut is always accessible and may be quickly and easily operated. The principle of operation

is the same in all three constructions and so far as the operator is concerned, what he has to do to effect adjustment is the same with any of the three constructions. The invention is defined in the appended claims 70 and I consider myself entitled to all forms and modifications of structure which fall within their scope.

I claim:

1. In combination in a multiple spindle 75 drill, a supporting arm, a drill spindle journal member vertically adjustable in relation thereto and means for clamping the journal member to the arm comprising a bar located between the arm and journal member 80 and seated at its upper end in the arm and between its ends against the journal member, said bar at its lower end being turned to the rear through the arm and receiving a nut, tightening or loosening of which will 85 clamp or release the journal member, substantially as described.

2. In combination, in a multiple spindle 90 drill, a supporting arm, a journal member for carrying a vertical spindle vertically adjustable relatively thereto and located at one end of the arm, and an elongated member disposed vertically between and housed between the end of the arm and the journal member and operatively associated 95 with said arm and journal member for releasably clamping the journal member to the arm and holding it against movement with respect to the arm, substantially as described.

3. In combination in a multiple spindle 100 drill, a supporting arm, a journal member located at one end of the arm and vertically adjustable relatively thereto, said journal member and arm having slots at their adjacent faces in which a bar is located; means for operatively joining the upper end of the bar with the arm, means for operatively joining the bar intermediate its ends to the journal member, said bar at its lower end 110 being turned to the rear and passing through a downward extension to the arm, and a nut threaded on the lower end of the bar to bear against said lower extension to the arm, substantially as and for the purposes described.

4. In combination in a multiple spindle 115 drill, a supporting arm, a journal member adapted to carry a rotatable spindle located at one end of the arm and adjustable vertically relative to the arm, said journal member and arm at their adjacent faces being provided with slots in conjunction with each other, a bar located in said slots, means for operatively joining the bar at a point between its ends with the journal member whereby said journal member may be moved vertically with respect to the bar, means for operatively joining the upper end of the bar with the arm, and means at the lower end of the bar operable to draw 120

the journal member against the end of the arm and clamp it firmly in position with respect thereto, said means being releasable to permit adjustment of the journal member, substantially as described.

5. In combination in a drill, an arm, a drill spindle carrying member located against one end of the arm and adjustable vertically with respect thereto, a bar located 10 between the arm and the spindle carrying member, means for pivotally and slidably mounting the upper end of the bar on the arm, means for pivotally and slidably mounting the bar at a point between its ends 15 on the spindle carrying member, and releasable means at the lower end of the bar engaging against the arm for securely clamping a spindle carrying member against the end of the arm, substantially as and for 20 purposes described.

6. In combination in a drill, a supporting arm, said arm at one end being provided with a T-slot extending downwardly from the upper side of the arm for a distance, and 25 with a downward extension having a vertical slot therethrough, a journal member adapted to carry a drill spindle located against the end of the arm, said journal member being provided with a vertical slot 30 adapted to come into conjunction with the slots in the arm, a bar located in said slots in the arm and journal member, lateral projections at the upper end of the arm extending into the wider portions of the T-slot 35 in the arm, means for operatively joining the bar between its ends to the journal member, said bar at its lower end being turned to the rear and passing through the vertical slot in the downward extension to the arm, 40 and a nut threaded on to said lower rearwardly turned end of the bar, substantially as and for the purposes described.

7. In combination, in a drilling machine, a supporting arm, said supporting arm at 45 one end being provided with a T-slot cut vertically in the arm from its upper side downwardly for a distance, a downward extension to said end of the arm having a vertical slot therethrough, a journal member 50 located against the end of said arm and provided with a slot cut vertically in the side thereof coming against the arm, the lower portion of said slot being formed into a T-slot, a bar located between the arm and 55 journal member and in the slots thereof,

lateral projections to the upper end of the bar extending into the wider portions of the T-slot in the arm, similar lateral projections on the bar between its ends extending into the wider portions of the T-slot in the journal member, said bar at its lower end being turned to the rear through the slot in the downward extension to the arm, and a nut threaded on to the lower rearwardly turned end of the bar, substantially as and for the 60 purposes described.

8. In a device of the character described, an arm, a journal member located against and vertically adjustable with respect to the arm, a bar between and housed within the 70 arm and journal member, and means connecting the bar to the arm and to the journal member for releasably binding said journal member against the end of the arm and permitting the journal member to be 75 moved vertically with respect to the arm when released, substantially as and for the purposes described.

9. In combination, a supporting arm, a 80 drill carrying spindle journal member located against the end of the arm, a bar operatively joined at a point between its ends to the journal member and having slidable connection to the arm at its upper end, said bar at its lower end extending through a downward extension to the arm, and releasable means on said lower end of the bar for clamping the journal member to the arm or releasing the same for vertical adjustment with respect to the arm, substantially 85 90 as and for the purposes described.

10. In a device of the character described, an arm slotted vertically at one end, a journal member located against said end of the arm and slotted so that the slots of the arm and journal member come into conjunction with each other, and means located within said slots and associated with the arm and journal member for adjustably mounting the journal member for vertical movements 95 with respect to the arm and holding the journal member against lateral movement with respect to the arm, said means being operable to clamp the journal member in 100 any position to which it may be adjusted with respect to the arm, substantially as 105 described.

In testimony whereof I affix my signature.

EDGAR W. CLEVELAND.
